UNITED STATES PATENT OFFICE

2,007,247

MASTER SHEET LAYING DEVICE FOR
DUPLICATING MACHINES

John W. Hernlund, La Grange, and Merritt G. Stewart, Chicago, Ill., assignors to Ditto, Incorporated, Chicago, Ill., a corporation of West Virginia

Application September 4, 1934, Serial No. 742,606

19 Claims. (Cl. 101—133)

This invention relates to duplicating machines and more particularly to a mechanism for laying a plurality of master sheets upon a duplicating surface such, for example, as the usual hectograph, or gelatin band.

In keeping the business records of certain types of enterprises, it is very often necessary to make cross references from one record to another when it is desired to determine certain results for totals. For example; in connection with oil wells, where an operating company may be keeping records upon several wells so as to know the amount of expense in connection with each well, this same operating company keeps records under the heading of the employees so that they may know the amount of wages paid to any individual employee. In such a case the operating company would have a record sheet which might have at one side, a row of names of employees, while across the top each well would be given a number of columns, two or three for example, and there would be such a record sheet for each day. Thus, we might have a worker being given credit for, say, three hours' work at Well No. 1 at a certain wage per hour, so that opposite his name, and under the columns marked "Well No. 1", the hours employed would be entered, the wage paid would be entered, and the total amount due the employee would be entered. On the same day that employee might work also at Well No. 3. There he would, perhaps, put in four hours and he might not have the same wage scale, or he might receive the same pay, so again, under Well No. 3, opposite the man's name, would be entered the hours of work, the pay per hour and the total.

It is evident from the above description, that when it is necessary to arrive at the total expenses for each individual well, the record, if it is to be condensed, must needs be copied off of these general sheets upon a separate sheet, similarly such copy work must be employed to keep the permanent records of the individual men.

It is the purpose of this invention to provide means whereby these original record sheets may be made with copying ink, and thereafter the transfers from the originals made by cutting up the original, or master sheets, of which there may be duplicates made for this purpose, into columns or sections and reassembling these sections so as to produce all the required data such, for example, as the required data concerning Well No. 1, upon a single copy.

It must be understood, of course, that the example given here, is merely to indicate the use to which the mechanism to be hereinafter described

is applied in connection with the duplicating process.

The handling of narrow strips of master sheets involves considerable difficulty in properly assembling them side by side, or in over-lapping relationship as required. So in order to be able to properly align these strips and over-lap them if desired, the original sheets which are to be divided up, are all punched alike, with rows of holes along the opposite side edges or end edges, as the case may be. These holes in the sheets are utilized, after the records are placed upon the sheets and the sheets are cut into separate sections, to align the sheets upon a master laying device in a manner which will be presently described.

The preferred form of the invention will be described by reference to the accompanying drawings wherein:

Fig. 1 is an assembled view partly in section, 20 showing the master sheet laying mechanism as applied to a hectograph machine of the flat bed plate type.

Fig. 2 is an enlarged sectional view taken on the line 2—2 of Fig. 1.

Fig. 3 is a side elevation partly in section of the pulley mechanism shown in section in Fig. 2.

Fig. 4 is a plan view of the machine with certain parts left out for sake of clearness.

Fig. 5 is a side elevation of the master sheet laying carriage.

Fig. 6 is a sectional view taken on the line 6—6 of Fig. 5.

Fig. 7 is a sectional view taken on the line 7—7 of Fig. 5.

Fig. 8 is a vertical section taken through one side of the master sheet laying carriage substantially on the line 8—8 of Fig. 11.

Fig. 9 is a fragmentary sectional view taken substantially on the line 9—9 of Fig. 11.

Fig. 10 is an enlarged sectional view of a detail of the mechanism for locking the laying carriage in home position.

Fig. 11 is a vertical sectional view taken on the line 11—11 of Fig. 8.

Fig. 12 is a vertical sectional view taken on the line 12—12 of Fig. 8.

Fig. 13 is a sectional view taken on the line 13—13 of Fig. 11.

Fig. 14 is a view like Fig. 13 but at the end of 50 the master sheet laying travel of the carriage.

Fig. 15 is a section on the line 15—15 of Fig. 11 showing the mechanism at the start of the laying operation.

Fig. 16 is an enlarged fragmentary sectional 55

view showing a changed position to that illustrated in Fig. 15.

Fig. 17 is a plan view of part of the bed plate and frame of the duplicating machine showing 5 the master sheets as they are placed upon the duplicating band.

Fig. 18 is a sectional view on the line 18—18 of Fig. 17.

Fig. 19 is a view like 18 with certain of the 10 parts in changed positions, and

Fig. 20 is a view like Fig. 18 showing the manner in which the margin bar is used in removing the master sheets from the duplicating band.

Referring now in detail to the drawings, the 15 machine to which this invention is applied is illustrated roughly in Fig. 1 as a duplicating machine of the flat bed type.

In the machine as shown F indicates the frame 20 of the machine. P indicates the printing bed. H indicates the hectograph band which may be wound on suitable rollers at opposite ends of the machine in the well known manner. The copying carriage is indicated in dotted lines at E, and the master sheet laying carriage is indicated 25 by M.

The duplicating machine may have the well known parts, such for example, as a standard margin bar, and the copying carriage may, of course, have the platen roller and other elements 30 such as are commonly found in machines of this character. These features, however, form no part of the present invention and will not be described further except where it is necessary to mention them to make the operation of the 35 device embodying the invention clear.

By reference to Fig. 1 it will be noted that the carriage M is lifted by means of suitable arms such as 20 from the full line position to the dotted line position shown in Fig. 1. This is accomplished in the following manner:

Upon the bracket 21 secured to the frame of the machine, the arm 20 is pivoted and a lever 22 is fixed to the arm 20. This lever is connected by means of the cable 23 to the pulley 24. The 45 cable passes around a suitable guide pulley 25 and is carried inside the frame as shown in Fig. 1, to the pulley 24 where it is clamped in place by means of the clamp 26. Pulley 24 is fixed to the gear wheel 27 which meshes with the worm gear 50 28 on shaft 29. Shaft 29 projects from the frame housing and is provided with a handle 30 by means of which it may be rotated.

From the above description it is evident that when the carriage M is secured to the arms 20, 55 of which there are two, the handle 30 may be turned to wind the cable 23 upon the pulley 24. This raises the carriage into the dotted line position shown in Fig. 1 so as to permit the use of the printing bed P and the hectograph band H with 60 the usual carriage for making copies from the hectograph band.

Now when it is desired to assemble master sheets of the kind herein before referred to and apply them to the duplicating band the carriage 65 M is brought down upon the frame F where these wheels, such as 31 and 32, ride upon the rails 33 and 34 mounted on the frame of the machine.

The carriage M is released from the arms 20 by lifting up the latch bar such as 35 out of the 70 notch 36 provided in the pin at the end of the arm 20. It is understood of course, that there are two latch bars 35, one for each arm, but the lifting up of one latch bar releases both of them because they are connected together by means 75 of the link 37. (See Figs. 4 and 7.)

With the carriage end released it can be moved to the left from the position shown in Fig. 1 to the limiting position shown in Fig. 5. At this point the projection 38 on the frame is engaged by the arm 39 pivoted on the carriage M and yieldingly pressed down by means of the spring 40. The carriage M is locked in this position by means of the locking lever 41. (See Figs. 5, 6, and 11.)

Lever 41, as shown, is pivoted to the carriage 10 frame at 42, and has a projection 43 which carries the pin 44. Slidable in the carriage frame, is the manually operable pin 45 and this pin, is normally pulled out to position shown in Fig. 11 15 so as to hold the lever 41 away from the member 39.

However, when the carriage M is in the position shown in Fig. 5 and the operator wishes to lock it there while he puts the master sheet on the carriage, he pushes the pin 45 into the position shown in Fig. 6 so that the pin 44 drops down into the groove 46 of the pin 45. This lets spring 47 move the lever 41 over on top of the member 39 to lock the carriage in position.

The carriage M carries a drum member 48 on 25 which the master sheets are mounted. This drum member has the shape of a segment of a cylinder and at one edge running lengthwise of the cylinder there is provided a row of securing pins 49, which pins project through slots (as indicated at 50 in Fig. 5) in the edge of the drum. This edge of the drum is extended as a sheet and turned under as indicated at 51, thus providing a channel which runs lengthwise of the drum. The pins 49 are supported in the heavier channel 30 member 52 which is mounted on the drum frame just inside the member 51.

Springs 53 and collars 54 co-operate to force the pins outward normally and to permit them to be pushed inwardly by pressure on their outer 35 ends.

The operator of the machine, in assembling the master sheets, places them on the drum with the record containing side facing outwardly and with the openings at the ends of the sheets fitted 45 over the pins such as 49. The record sheets are shown in place in Fig. 5 and indicated by the numeral 55.

When the operator has secured the one end of each record sheet in place on the pins 49 he turns 50 the drum in a clockwise direction as shown in Fig. 5 so as to gradually press the record sheets smoothly down on the drum throughout the length of the sheets.

A roller 56 mounted on the carriage M by 55 means of the arms, such as 57, co-operates with the drum surface to roll the master sheets down smoothly. At the beginning of the advancement of the drum the roller 56 is moved back by means of the pins 49 against the tension of the spring 60 58 to the position shown in dotted lines in Fig. 5 and there is passed over the pins due to the fact that it is off center with respect to the drum and thereafter it continues to roll the master sheets down smoothly. When the drum is rotated to its 65 limit in a clockwise direction the stop member 59 strikes the pin 45. At this instant the pins 49 are in the position shown in Fig. 9; that is, they align with corresponding pins 60 mounted upon the master sheet margin bar 61. The details of 70 this margin bar will be more clearly explained hereinafter.

With the pins 49 and 60 directly aligned with each other, the next step in the operation is to 75 transfer the master sheets from the pins 49 to

the pins 60. Before describing that, however, it should be mentioned that the other end of each master sheet is so secured on the drum by having the openings therein threaded over the pins 62. These pins 62 are all carried upon a bar 63 (see Figs. 12 and 16). The pins also work through slots provided in the edge of the drum sheet in the same fashion that pins 49 do. The bar 63 is supported at its opposite ends by a pair of pins 64 and 65. These pins are carried by the channel member 66 and are movable in and out with respect to the channel member within the limits permitted by the collars 67 and 68 and the springs 69 and 70. For actuating the pins 64 and 65 there is provided a bar 71 which has rollers 72 and 73 adapted to engage the stripping cams 74 and 75. Going back now, to the operation whereby the master sheets are transferred from pins 49 to pins 60, it will be noted from an inspection of Fig. 8 that the upper, or drum carrying portion of 76 of the carriage M is spaced above the lower portion 71 thereof in Fig. 5 and in Fig. 9, while in Fig. 8 the portion 76 has been forced down until it contacts the portion 71. The operator does this manually by pressing down upon the carriage so as to compress the springs 78 and 79 which are seated in the recessed member 71 and encircle the mounting pins 80 and 81. When the entire drum supporting structure is thus depressed, the drum is brought down against the gelatin band H as shown, for example, in Figs. 8 and 15, and latched in down position by means of latch 83 engaging with latch block 77 as shown in Fig. 11. The pins 60 push the pins 49 up with respect to the drum against the pressure of the springs on the pins 49. In this way, the master sheets are transferred from the drum to the surface of the gelatin band without any movement being possible to disarrange them. The downward pressure of the frame 76 thus prepares the carriage for its rolling operation to spread the master sheets out upon the duplicating band.

By referring to Fig. 6 and Fig. 11, the manner in which the carriage M is released so that it can be advanced will be more clearly understood in connection with the following description:

As shown in Fig. 6, the frame 76 has mounted thereon the latch 82 which is notched as indicated at 83, and, when the member 76 is pressed down, this notch passes below the edge of the shoulder 84 and snaps into place so as to latch the member 76 in its lowered position. The spring 85, of course, urges the latching member in the proper direction so as to hold it in place as soon as it snaps over the shoulder 84. There is a latching member on each side of the machine, as is shown clearly by Fig. 11. The operator next pulls out the pin 45 so as to throw the lever 41 out of locking position, and the carriage is ready to advance. By pushing the carriage the member 39 is caused to ride over the stop 38 since it is no longer locked in position and the carriage is moved from left to right; that is, from the position shown in Fig. 13 to that shown in Fig. 14. As the carriage nears the position shown in Fig. 14 the rollers 72 and 73 engage on their respective cam members 74 and 75 and the pins 64 and 65 are drawn inward to withdraw the holding pins 62 and release the master sheets without any danger of injuring them. At this point it is also necessary to release the latches 83 to permit the drum and its mounting members 76 to rise so that if the carriage is turned back the edges of the master sheets will not be damaged. This is accomplished by providing, on the

drum member, a pair of cams 86 and 87, which cams engage the rollers 88 and 89 which are mounted on the bell crank levers 90 and 91 fixed to the lower frame member 77 of the carriage and connected by links 92 and 93 with the latch members 83.

It is believed to be evident from an inspection of Fig. 11 that pressure downward upon the rollers 88 will pull the latch members 83 out of latching position and permit the drum mechanism to rise to original position.

In order that the drum itself will not tend to rotate out of its limiting positions, the drum mounting shaft 94 (see Fig. 12) has a collar 95 thereon which carries a spring pressed ball 96 that is adapted to seat itself in the depressions 97 and 98 in the two limiting positions of the drum.

After the cams 86 and 87 permit the drum to rise the entire carriage M is shoved on further along the frame until the pins on the ends of the frames 20 extend into the sockets on the carriage and thus secure the carriage to the arms 20. The operator then can lift the carriage by turning the crank 30 and when the master sheets are removed from the gelatin band he will be ready to use the regular copy carriage E for making copies off the impression made on the gelatin band. The master sheets are stripped off the gelatin band by utilizing the special master sheet margin bar 61. This margin bar rests on the frame and is positioned at its opposite ends by means of the projections 100 and 101 on the frame which stick up through holes provided in the margin bar. The margin bar has a clamping section 102 hinged to the main section which carries the pins and this clamping section is normally in the position shown in Fig. 18, for example, where the stop 103 striking the apron 104 on the pin carrying portion of the margin bar 40 limits the downward movement of the portion 102. When it is desired to remove the master sheets from the gelatin band however, the hinged portion 102 is folded over into the position shown in Fig. 19 and the entire margin bar 45 is lifted up as indicated in Fig. 20 to lift the master sheets off of the gelatin band. It will be noted that the edge of the margin bar at 105, closest to the gelatin band, is tapered so as to get the pins thereon as close as possible to the 50 gelatin band. Of course after the master sheets and special margin bar are removed the carriage E may be used to produce copies from the gelatin band in the usual manner.

In placing the master sheets on the drum 48 it is evident that where sheets are laid over one another as shown in Fig. 16 at 55 and 55' the outer sheet must traverse a greater distance between the pins 49 and 62 than the distance between these pins along the drum surface because of the thickness added by the inner sheet. To take care of this matter and inequalities in punching sheets a limited amount of adjustment of pins 62 is provided. Bar 66 is carried by arms 107 and 108 which are pivoted on the hubs of the drum 48 as shown at 109 and 110 in Figs. 12, 15 and 16. The arms 107 and 108 are secured in position by means of screw bolts, 111 which pass through openings 112 in the hub portions of the arms, and are threaded into the drum hubs. Plates 113 and 114 are held in place by the screw bolts, and prevent the arm hubs from sliding over the heads of screw bolts 111. It will be noted that the openings 112 are somewhat 75

- larger than the bolts 111. This permits a limited amount of turning of the arms and therefore of the pins 62 with respect to the drum. The springs 115 interposed between the drum frame and projections 117 on the arms 107 and 108 hold the arms and pins 62 normally in the position shown in Fig. 15 but permit them to move slightly as shown in Fig. 16 to fit the holes in the outer sheets such as 55' over the pins 62.
- 10 While certain embodiments of the invention have been shown and desired, it is to be understood that it is capable of many modifications. Changes, therefore, in the construction and arrangement may be made without departing from 15 the spirit and the scope of the invention as disclosed in the appended claims in which it is the intention to claim all novelty inherent in the invention as broadly as possible in view of the prior art.
- 20 The invention having thus been described, what is claimed as new and desired to be secured by Letters Patent is:
1. A duplicating machine having a main frame, a duplicating surface thereon, a master sheet laying carriage, and a copy sheet laying carriage, and means for moving one of said carriages up from the duplicating surface out of the path of the other.
  2. A duplicating machine having a main frame, a duplicating surface thereon, a master sheet laying carriage having means thereon for mounting a plurality of master strips, record side up, and holding them assembled as a unit, and means for inverting the assembled strips to apply them to the duplicating surface.
  3. A duplicating machine having a main frame, a duplicating surface thereon, and a master sheet assembling and laying device comprising means for securing together a plurality of master sheets, printed side up, and inverting them and laying them upon the duplicating surface.
  4. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets.
  5. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets, and a carriage movable over the frame, said drum being rotatably mounted on said carriage.
  6. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets, and a carriage movable over the frame, said drum being rotatably mounted on said carriage, and vertically movable on said carriage.
  7. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets, and a carriage movable over the frame, said drum being rotatably mounted on said carriage, and vertically movable on said carriage.
  8. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets consisting of opposed rows of mounting pins on which openings in the master sheets may be threaded.
  9. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets consisting of opposed rows of mounting pins on which openings in the master sheets may be threaded, said pins being movable radially inward with respect to said drum.
  10. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets consisting of opposed rows of mounting pins on which openings in the master sheets may be threaded, said pins being movable radially inward with respect to said drum.
  11. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets consisting of opposed rows of mounting pins on which openings in the master sheets may be threaded, and means providing for circumferential movement of one row of pins with respect to the other.
  12. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets consisting of opposed rows of mounting pins on which openings in the master sheets may be threaded, and a margin bar on said frame having pins cooperating with the drum pins to transfer the assembled sheets to said duplicating surface.
  13. A duplicating machine having a main frame, a duplicating surface thereon, and a master sheet assembling and laying device comprising means for securing together a plurality of master sheets, printed side up, and inverting them and laying them upon the duplicating surface, and a removable margin bar having means receiving one end of said sheets from the laying device.
  14. A duplicating machine having a main frame, a duplicating surface thereon, and a master sheet assembling and laying device comprising means for securing together a plurality of master sheets, printed side up, and inverting them and laying them upon the duplicating surface, and a removable margin bar having means receiving one end of said sheets from the laying device, said margin bar having gripping means thereon to hold the sheets assembled for stripping them from the duplicating surface.
  15. A duplicating machine having a main frame, a duplicating surface thereon, and a master sheet assembling and laying device comprising means for securing together a plurality of master sheets, printed side up, and inverting them and laying them upon the duplicating surface, and a removable margin bar having means receiving one end of said sheets from the laying device, said margin bar having gripping means thereon to hold the sheets assembled for stripping them from the duplicating surface.
  16. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets consisting of opposed rows of mounting pins on which openings in the master sheets may be threaded, said pins being movable radially inward with respect to said drum, and a margin bar on said frame having pins cooperating with the drum pins to transfer the assembled sheets to said duplicating surface.

14. A duplicating machine having a main frame, a duplicating surface thereon, and a master sheet assembling and laying device comprising means for securing together a plurality of master sheets, printed side up, and inverting them and laying them upon the duplicating surface, said means comprising a drum having mounting means for said sheets consisting of opposed rows of mounting pins on which openings in the master sheets may be threaded, said pins being movable radially inward with respect to said drum, and a margin bar on said frame having pins cooperating with the drum pins to transfer the assembled sheets to said duplicating surface, said margin bar pins being aligned with one row of drum pins during downward movement of the drum.
15. A duplicating machine having a main frame, a duplicating surface thereon, a master sheet laying carriage having means thereon for mounting a plurality of master strips, record side up, and holding them assembled as a unit, and means for inverting the assembled strips to apply them to the duplicating surface, said means comprising a drum having sheet securing means thereon.
16. A duplicating machine having a main frame, a duplicating surface thereon, a master sheet laying carriage having means thereon for mounting a plurality of master strips, record side up, and holding them assembled as a unit, and means for inverting the assembled strips to apply them to the duplicating surface, said means comprising a drum having sheet securing means thereon, said drum being vertically movable to bring the sheets thereon down upon the duplicating surface.
17. A duplicating machine having a main frame, a duplicating surface thereon, a master sheet laying carriage having means thereon for mounting a plurality of master strips, record side up, and holding them assembled as a unit, and means for inverting the assembled strips to apply them to the duplicating surface, said means comprising a drum having sheet securing means thereon, said drum being vertically movable to bring the sheets thereon down upon the duplicating surface, and locking means for locking the drum in lowered position.
18. A duplicating machine having a main frame, a duplicating surface thereon, a master sheet laying carriage having means thereon for mounting a plurality of master strips, record side up, and holding them assembled as a unit, and means for inverting the assembled strips to apply them to the duplicating surface, said means comprising a drum having sheet securing means thereon, said carriage being movable over the duplicating surface to transfer the sheets from the drum to the duplicating surface.
19. In a duplicating machine, a supporting device for master sheets having means to secure a plurality of strips of master sheets thereon with the printed side up, and a margin bar having means thereon to receive and hold one end of the assembled sheets, said bar cooperating with said device to position the assembled sheets face down on the duplicating surface.

JOHN W. HERNLUND.
MERRITT G. STEWART.
